UNITED STATES PATENT OFFICE.

GEORGE H. HORNE, OF GLENDALE, CALIFORNIA, ASSIGNOR TO INTERNATIONAL PRECIPITATION COMPANY, OF LOS ANGELES, CALIFORNIA, A CORPORATION OF CALIFORNIA.

APPARATUS FOR ELECTRICAL PRECIPITATION OF SUSPENDED MATERIAL FROM GASES.

Application filed April 13, 1925. Serial No. 22,847.

To all whom it may concern:

Be it known that I, GEORGE H. HORNE, a citizen of the United States, residing at Glendale, county of Los Angeles, State of California, have invented a new and useful Apparatus for Electrical Precipitation of Suspended Material from Gases, of which the following is a specification.

This invention relates to apparatus for electrical precipitation of suspended materials such as dust, fume or mist from gases containing the same and particularly to apparatus for this purpose in which the collecting electrodes are formed of semi-conducting material such as concrete and are provided with metallic conducting and reinforcing members embedded therein.

An important object of the present invention is to provide an advantageous relative arrangement of said embedded conducting and re-enforcing members with respect to the discharge electrode means so as to simplify the construction and improve the operation of the precipitator. My invention may be applied in connection with a collecting electrode of the above type consisting either of an integral plate or built up of sectional units but certain advantages of the construction herein described are more fully realized in the case of a sectional construction than in an integral construction as will be pointed out more fully hereinafter.

The accompanying drawings illustrate embodiments of my invention and referring thereto:

Fig. 1 is a longitudinal vertical section of an electrical precipitator embodying my invention and provided with sectional collecting electrodes.

Fig. 2 is a transverse vertical section of the form of the invention shown in Fig. 1.

Fig. 3 is a partial horizontal section of one of the collecting electrodes shown in Fig. 1 and of the adjacent discharge electrodes.

Fig. 4 is a partial side elevation of one of said collecting electrodes and the adjacent discharge electrodes.

Fig. 5 is a partial side elevation of a collecting electrode in which the metallic reinforcing and conducting members are not metallically grounded.

Fig. 6 is a partial horizontal section of the collecting electrodes shown in Fig. 5

and the adjacent discharge electrodes.

Fig. 7 is an enlarged partial side elevation of the electrode means shown in Fig. 5. 55

Fig. 8 is a side elevation of an integral collecting electrode together with the adjacent discharge electrode means adapted for use in a precipitator of the type shown in Fig. 1. 60

Fig. 9 is a partial longitudinal vertical section of the collecting electrode shown in Fig. 8.

Fig. 10 is a longitudinal vertical section 65 of an electrical precipitator showing another embodiment of my invention.

Fig. 11 is a transverse section of the electrical precipitator shown in Fig. 10.

Fig. 12 is an enlarged partial side elevation of one of the collecting electrode means shown in Fig. 10 together with the adjacent discharge electrode members. 70

Fig. 13 is a horizontal section on line 75 13—13 in Fig. 12.

In the form of the invention shown in Fig. 1 the precipitator chamber or housing is indicated at 1 and is shown as provided with suitable inlet means 2 and outlet means 3 for passage of gas therethrough and with suitable means at the bottom of said chamber such as hopper 4 adapted to receive the precipitated material. Any suitable means may be provided for removing such material from said hopper. The above described structure including the precipitator chamber and inlet and outlet and material-receiving means may be formed of any suitable material and in some cases may advantageously be constructed as shown of concrete or similar material. Within said chamber 1 are located a plurality of discharge electrode elements 5 and collecting electrode means 6. 80

The discharge electrode elements 5 may consist of wires or small rods of relatively small cross-section and therefore of relatively small surface area and sharp surface curvature and in this case are shown as suspended vertically within the precipitator chamber. Any suitable means may be em- 85

ployed for supporting said discharge electrode elements such as horizontal supporting rods 8 resting on end frames comprising horizontal members 9 and vertical members 10 and said end frames being 100 supported in turn by bus bars 11 resting 105

- on suitable insulating supports 12. Tensioning means such as weights 13 may also be provided at the lower ends of said discharge electrode elements for causing said elements to hang in the proper position and suitable means such as bars 14 may also be mounted on the above described end frames and adapted to aline and space said tensioning means and discharge electrode elements.
- Each collecting electrode 6 comprises a plurality of horizontal sections 16 mounted one above another so as to form a substantially continuous collecting electrode plate.
- I prefer to provide at the bottom of each collecting electrode a base section 17 which is somewhat longer than the remaining sections and is adapted to rest at its outer ends upon suitable supporting means such as ledges 18 formed in the precipitated housing and to support the upper sections 16 of the collecting electrode. Said sections 16 may be alined and held in position at their ends by suitable supporting frame means such as channel irons 19 and supported for example by suitable means such as lateral beams or channel irons 20. The sections 16 of the collecting electrode plates are formed of suitable semi-conducting material such as Portland cement concrete, terra-cotta, or other plastic composition or cementitious material, which has a relatively low electrical conductivity, and they may be held together at their adjoining edges by means of tongue and groove joints and also if desired by means of mortar or cement grout. In order to strengthen and re-enforce said sections and also cause uniform distribution of electrical potential to all parts thereof I prefer to provide metallic conducting and re-enforcing members 22 extending horizontally within said sections and metallically grounded, for example by connection with the metallic supporting members 19. Said conducting and re-enforcing members may consist of wires or of smooth or twisted rods and said rods may be either round or square or of any other suitable shape. The base section 17 may also be provided with suitable re-enforcing and conducting means indicated at 23 and said means may also be grounded by connection with the metallic frame members 19. It is not necessary in all cases however that the metallic re-enforcing and conducting means 22 as well as 23 be in metallic connection with the ground and in some cases I may prefer to eliminate such connection as shown in Figs. 5 to 7. In such cases the members 22 stop a short distance from the ends of the sections 16 and are therefore out of connection with the supporting members 19 and the re-enforcing means 23 are similarly out of connection with said means 19. Or if desired the re-enforcing and conducting members 22 and 23 may be connected to said metallic supporting means 19 as in the form first described, but said supporting means may not be metallically grounded, but may be grounded only through the concrete or other semi-conducting material of which the precipitator housing is constructed.
- Any suitable spacing may be provided between the discharge electrode elements 5 and also between the embedded conducting and re-enforcing members 22, for example as shown the spacing between the said members 22 may be somewhat greater than the spacing between the discharge electrode elements 5 and it should be noted that there need be no definite inter-relation between the respective spacings of said members.
- The discharge electrode system may be connected for example through wire indicated at 25 to one side of a source of high tension current, either alternating or direct, but preferably rectified alternating current, the other side of which source is grounded. Said source of high tension current is preferably adapted to maintain a potential difference between the discharge electrodes and the grounded collecting electrodes of from say 15,000 to 100,000 volts. The exact voltage required in any case depends upon the spacing of the electrodes, the nature of the gas being treated, and upon other conditions. The collecting electrode system is preferably grounded as indicated at 26, said grounding being actually accomplished for example by connecting a grounded wire to a suitable part of the metallic supporting means for the collecting electrodes. When so grounded it will be seen that in the forms shown in Figs. 1 to 4 the re-enforcing and conducting members 22 are in direct metallic connection with the ground so that all portions of the collecting electrodes are maintained at all times at substantially the potential of the earth. In the form of the invention shown in Figs. 5 to 7 on the other hand the re-enforcing and conducting members 22 are not in direct metallic connection with the ground but are only in connection therewith through the high resistance or semiconducting material of the electrode between the ends of said members 22 and the side frames 19. This may be of advantage in some cases in that while the conducting members 22 serve to maintain all portions of the collecting electrode at substantially uniform potential the interposition of the high resistance material at the point above mentioned between said conducting members and the ground prevents the flow of sufficient current to or from any portion of one of said conducting members to cause disruptive discharge, as may be the case when said members are in direct metallic connection with the ground. It should be noted however that the members 22 serve in either

case not only to mechanically re-enforce the sections 16 of the collecting electrodes but also to maintain substantially uniform distribution of electrical potential at the surface thereof.

In the operation of this form of the invention the electrode system is energized by connection to the source of high tension current as above described and by reason of the 10 relatively small surface area and sharp curvature of the discharge electrodes and the relatively extended area of the collecting electrodes, a silent discharge is produced from the former to the latter. The gas to be treated is passed through the chamber 1 so as to flow substantially horizontally between the discharge electrodes and the collecting electrodes. Under the action of the 15 electrical discharge the suspended particles carried by the gas become charged and are attracted to the collecting electrodes 6. The material so precipitated eventually falls off the collecting electrodes by gravity and collects in the hopper 4 at the bottom of the 20 precipitator from which it may be removed in any suitable manner either continually or from time to time. If desired or found necessary the collecting electrodes may be jarred or rapped from time to time to dislodge deposited material therefrom but it 25 has been found with semi-conducting materials such as concrete that the deposited material adheres thereto in a relatively loose manner and therefore falls off by its own 30 weight before it becomes thick enough to seriously impair the effective operation of the precipitator.

One advantage of the above described construction is that there need be no definite 40 relation between the spacing of the discharge electrode elements 5 and the spacing of the re-enforcing members 22. This form of construction is therefore to be distinguished from previously described constructions in which the collecting electrodes were formed of semi-conducting material 45 and were provided with re-enforcing and conducting members extending parallel to the discharge electrode elements. In those cases it has been necessary to preserve 50 throughout the precipitator a substantially uniform relation between the spacing of the discharge electrode elements and the spacing 55 of the re-enforcing and conducting members in order that none of the embedded conducting members shall be appreciably closer 60 to an adjacent discharge electrode element than are any of the other embedded conducting members, so as to prevent concentration 65 of the electrical field in the portion of the collecting electrode adjacent said embedded member. Such accurate positioning of the electrodes is not always practicable, in some cases, and in such cases, the use of 70 my form of construction is desirable, as with

such a construction there is no possibility of any one of the embedded conducting members being in closer proximity to the discharge electrode means than any of the other embedded conducting members, so that concentration of the electrical field to the portion of the collecting electrode adjacent one of said embedded conductors is therefore impossible.

Furthermore it has been found that 75 in some cases it is desirable for the most effective operation of the precipitator to provide a different spacing between the embedded conducting members 22 and between the collecting electrode elements 5. For example the form of the construction shown in Fig. 1 in which the embedded conducting members are spaced at a somewhat greater distance apart than the discharge 80 electrode elements may be very effective in 85 some cases. The spacing between adjacent embedded members 22 may for example be approximately one and one half times the spacing between adjacent discharge electrode elements 5.

A further advantage of this form of construction arises from the fact that it is often necessary in construction of electrical precipitators to make the collecting electrodes relatively high and narrow and in such cases 90 it is much more desirable, when a sectional type of collecting electrode is used, to construct the plates of horizontal sections 16 one above another rather than to form said plates of a plurality of vertical sections one 95 100 beside another. It is therefore often unavoidable when using a sectional construction of the collecting electrode plates that the breaks between adjacent sections extend horizontally as indicated at 28 in Fig. 1. 105 It has also been found in certain cases very undesirable to have the embedded re-enforcing and conducting members extending across said breaks between adjacent sections 110 because of the fact that said re-enforcing members thereby become relatively exposed at such points especially in case of failure to make a perfectly tight joint at such points, and disruptive discharge is therefore very apt to occur between the discharge electrodes and the exposed parts of the embedded re-enforcing members at these joints. It is therefore desirable in a treater 115 of this type, in order to have the embedded re-enforcing members extend continuously 120 throughout substantially the entire length of the collecting electrode without crossing any joints between sections, and at the same time have the collecting electrode sections extend horizontally one above another, that each of said sections be provided with one 125 or more embedded re-enforcing and conducting members extending horizontally within said section and substantially throughout the entire length thereof. It 130

has also been found however that it is much more advantageous to have the discharge electrode elements extend vertically rather than horizontally in many cases in which 5 such sectional collecting electrode construction is used, due to the difficulty in preserving proper alinement and tensioning of horizontal discharge members of sufficiently small cross-section to produce the most effective electrical discharge. The construction according to my invention in which the discharge electrode elements extend vertically and the embedded conducting members extend horizontally, therefore not only 10 accomplishes the advantageous results above described of permitting the variation between the spacing of the discharge members and the embedded conductors and preventing concentration of the electrical field 15 due to any one of said embedded conductors being closer to the discharge electrodes than the other embedded conductors, but also permits both the embedded conductors and the discharge electrode elements to extend 20 in the most desirable direction for effective electrical precipitation.

Certain of the above mentioned advantages of my invention may however be realized even when the collecting electrodes 30 are not of sectional construction but each 35 of said collecting electrodes is made as an integral unit. For example as shown in Fig. 8 each collecting electrode 6 may comprise an integral plate of concrete or other semi-conducting material resting as before 40 on base section 17 and supported in suitable frame means 19 at both sides. Said collecting electrode plate may advantageously be provided with horizontally extending 45 embedded conducting and re-enforcing members 22 which may be metallically grounded as shown by connection to said side frames 19, or as above described may stop at a slight distance from said side 50 frames so as to be grounded only through the intervening portion of the semi-conducting material of the collecting electrode. It will be noted that in this form of the invention also the discharge electrode elements 55 extend vertically while the embedded conductors extend horizontally so that there need be no definite relation between the spacing of said discharge electrode elements and said embedded conductors. The above 60 mentioned advantages arising from this feature of the invention namely the fact that the spacing between the embedded conductors may be made somewhat greater than the spacing between the discharge electrode elements if desired and also that a failure to 65 preserve uniform spacing between said embedded conductors and uniform relation between the said embedded conductors and said discharge electrode elements will not cause concentration of the electrical field at

a portion of the collecting electrode opposite one of said embedded conductors which is closest to an adjacent discharge electrode element, are realized in this form of construction as well as in the sectional construction first described. 70

My invention is not limited to the above described forms of construction in which the discharge members extend vertically and the embedded conductors horizontally but it 75 should be understood to include any construction in which said embedded conductors and discharge members extend transversely or at right angles to one another. For example as shown in Figs. 10 to 13 inclusive the collecting electrode may be formed as an integral plate 6 of concrete or other semi-conducting material and the embedded conductors 22 may extend vertically 80 therein while the discharge electrode members 5 extend horizontally. Said discharge electrode members may be supported by suitable frame means as shown resting on insulating supports 12 and said collecting electrode plates may be supported by means 85 of channel irons or other suitable supporting members 30 extending along their upper edges and secured thereto in any suitable manner. Said supporting members 30 may in turn rest on supporting means such as 90 Z-bars 31 at the top of the precipitator housing 1. The collecting electrode plates 6 may be secured to and suspended from said supporting members 30 by means of beams or channel irons 32 at the bottom of said 95 plates and tie-rods 33 at the edges of said plates and secured at their ends to supports 30 and 32. The supporting means 30, 32, and 33 therefore comprise a metallic conducting and supporting frame for said 100 collecting electrode plate and serve not only to support said plate but also to ground the same, for example through ground wire indicated at 26. The embedded conductors 22 may as before be metallically grounded by 105 connection at their ends to the frame members 30 and 32 or said embedded conductors may if desired stop somewhat short of said frame members so as to be in connection with the ground only through the intervening portion of the semi-conducting 110 material of the electrode. In either case however said members 22 serve to both mechanically re-enforce the collecting electrode plate and to maintain substantially 115 uniform distribution of electrical potential to the collecting surfaces thereof. It will be observed that in this case as before the discharge electrode members and the embedded 120 conductors extend perpendicularly to one another, and that consequently there need be no definite relation between the spacing of said members, for the reasons above mentioned, and the above described advantages 125 arising from this fact are therefore realized. 130

The electrical connections and the operation of the two last-described forms of my invention, provided with integral collecting electrodes, may be substantially the same as 5 above described.

What I claim is:

1. In an electrical precipitator a collecting electrode formed of semi-conducting material and provided with metallic members 10 embedded therein and extending horizontally, and discharge electrode means adjacent said collecting electrode means and comprising a plurality of vertically extending members of relatively small cross-section.
- 15 2. In an electrical precipitator a collecting electrode consisting of semi-conducting material and provided with a plurality of metallic members embedded therein and extending substantially throughout the length 20 thereof, and discharge electrode means adjacent said collecting electrode and comprising a plurality of members extending transversely to said embedded members.
- 25 3. In an electrical precipitator a collecting electrode comprising a plate of semi-conducting material, grounded metallic frame means supporting said plate, embedded metallic members within said plate, and connected at their ends to said metallic frame 30 means and discharge electrode means mounted adjacent said plate and comprising a plurality of members extending transversely to said embedded members.
- 35 4. In an electrical precipitator a collecting electrode comprising a plurality of sections

mounted one above another to form a plate, said sections being formed of semi-conducting material, metallic members embedded within said sections and extending horizontally therein, and discharge electrode means 40 adjacent said collecting electrode and comprising a plurality of vertically extending members.

5. In an electrical precipitator a collecting electrode plate comprising a plurality of 45 super-posed sections of semi-conducting material, grounded metallic supporting means engaging said sections at their ends, metallic members embedded within said sections and extending horizontally therein and connected at their ends to said metallic supporting means, and discharge electrode means comprising a plurality of members extending vertically adjacent said collecting 50 electrode plate.

6. In an electrical precipitator a collecting electrode plate formed of semi-conducting material, a plurality of metallic members embedded within said material and extending parallel to one another, and discharge 60 electrode means comprising a plurality of members extending transversely to said embedded members, the spacing between said embedded members being unequal to the spacing between the members of said discharge electrode means.

In testimony whereof I have hereunto subscribed my name this tenth day of March, 1925.

GEORGE H. HORNE.
